UNITED STATES PATENT OFFICE

THOMAS WALTER HORN, OF CLEVELAND, OHIO

PAPER FEEDER

Application filed August 26, 1929. Serial No. 388,407.

This invention relates to improvements in paper feeders, particularly to means for feeding sheets of paper in close succession to a printing machine or other paper handling machine.

One of the objects of the invention is the provision of a feeder which shall include paper straightening means operating effectively upon sheets moving in close succession, 10 and without damage to the sheets, such feeding of sheets in close succession being necessary where the printing area of the printing roll covers approximately the entire surface of the roll.

Another object is the provision of means for swinging the rear edge of each sheet out of the direct path of movement of the sheets after its forward edge is gripped by a positive feeding means, such as the printing rolls 20 of a printing machine, whereby the straightening stop fingers may be advanced into the path of movement of the sheets without encountering and damaging the rear edge of the sheet then in process of being printed.

Another object is the provision of simple means for adjusting the feed of the sheets with respect to the printing surface of the printing roll, whereby the margin at the top of the sheet may be varied.

A further object is the provision of simple means for declutching the sheet feeder, and for directing the feed of a paper web into the printing machine to one side of the sheet feeder, so that paper in either sheet or web form may be employed.

Other objects and features of novelty will appear as I proceed with the description of that embodiment of the invention which, for the purposes of the present application, I have illustrated in the accompanying drawings, in which:

Fig. 1 is an end view, partially in section, of a feeder embodying my invention in assembled relation with a Rotaprint machine, certain principal elements of the latter being illustrated for the most part in a diagrammatic manner;

Fig. 2 is a top plan view of the feeder 50 alone;

Fig. 3 is a side elevational view of the same;

Fig. 4 is an end elevation of the feeder;

Fig. 5 is a fragmental elevational view of the fixed guide; 55

Fig. 6 is a side elevational view showing my feeder mounted in a Rotaprint machine and operatively connected with a pile feeder;

Fig. 7 is a plan view of a sheet guiding means; 60

Fig. 8 is a side view of the stripper bar;

Fig. 9 is a longitudinal sectional view of the same;

Fig. 10 is an end elevational view, somewhat diagrammatic in character, illustrating 65 the sheet stripper bar and sheet delivery guide fingers;

Fig. 11 is a detail longitudinal sectional view of the combined clutch and feed regulating means; and 70

Fig. 12 is an end view of the same, taken partly in section on the line 12—12 of Fig. 11.

Similar reference characters refer to like parts throughout the views.

Referring first to Fig. 6, I have illustrated 75 therein a preliminary sheet feeding means serving to separate the sheets from a pile or stack and direct them one by one and in close succession into my sheet feeder. This mechanism may be of any known or suitable form. That illustrated herein is a pile feeder comprising a frame 10, a vertically movable platform 11 upon which the pile of sheets 12 is supported, an oscillating suction head 13 pivoted at 14 and operatively 80 connected with a suction line 15, and a pair of positively rotated feed rolls 16 and 17. 18 is a tape conveyor driven in the direction indicated by the arrow for carrying sheets from the pile feeder to my improved sheet 85 feeder, the latter being mounted within the casing 19 of a Rotaprint or other paper handling machine, which may be supported upon suitable legs 20.

My feeder is so designed as to be quickly 90 and easily mounted upon a Rotaprint machine as now manufactured and sold. These machines comprise frame rods 21 and 22, and it is upon these rods that I support my feeder 95 exclusively, no changes whatever in the Rota- 100

print machine being required, and no bolt holes being necessary. The end frame members of my feeder are indicated generally at 23. These members are connected by parallel rods 24, 25 and 26, having shouldered and threaded ends for the reception of clamping nuts, so that the side members of the frame are properly spaced and securely held together. The side members 23 have secured thereto, by bolts 27, shoes 28 which are recessed to fit over the rod 21 of the Rotaprint machine. A pair of hook bolts 29, mounted in the frame of the tape conveyor 18, serve the double purpose of holding the shoes 28 on the rod 21 and of securing the tape conveyor to the Rotaprint machine. Near the ends of the rod 24 I mount U-clamps 30, provided with holes through which extend supporting rods 31 having nuts 32 and 33 thereon for gripping the outer sides of the U-clamps. At their lower ends these rods carry C-shaped clamps 34 that are movable upon the rods 31 and may be held by nuts 35 and 36 in position to clamp the rod 22 of the Rotaprint.

The tape conveyor comprises a driven roll 37 and a pressure roll 38 which holds the sheets in contact with the tapes 18 passing over the roll 37, thereby assisting in the feed of the sheets into the flaring mouth of a fixed sheet guide comprising upper and lower guide plates 39 and 40 which extend entirely across the feeder.

The upper edge of plate 39 is notched out at regular intervals, as shown in Fig. 5, so as to permit the feed rolls or wheels 41 to protrude therethrough. These wheels are mounted upon a sleeve 42 which is rotatably supported at its ends upon pins 43 carried by blocks 44 which are grooved to slide upon spaced parallel guide elements 45 of brackets 46, that are mounted upon the side members 23 of the feeder frame. Interposed between each block 44 and the end of the corresponding bracket 46 is a coil spring 47 which tends to force the block 44 inwardly. On the pins 43 there are cam followers 48 to be referred to again presently.

A shaft 50 extends through the feeder from end to end, being mounted in bearings 51 and 52 carried by the end walls 23. On this shaft 50 at regular intervals are secured feed sectors 53, these sectors being secured to the shaft 50 by means of semi-circular clamps 54 which are attached to the sectors by studs 55. The sectors 53 have peripheries of circular contour which enter slots of suitable size and form in the guide plate 40. The sectors 53 are positioned directly opposite the rollers 41 and are adapted to cooperate therewith for feeding sheets of paper. While I prefer to make these sectors of semi-circular form, in order to leave the space between the guide plates 39 and 40 entirely unobstructed during a portion of the cycle of operations, it is

quite possible to substitute completely circular elements if desired.

Near the ends of the shaft 50 just within the end members 23 of the frame, I fix to the shaft two sets of cams 56, 57 and 58. The largest cams 56 are adapted to engage the cam followers 48 and to hold the rollers 41 out of contact with the sectors 53 while the followers 48 run upon the outer periphery of the cam, and permitting the springs 47 to force the rollers 41 into contact with the sectors when the followers are running upon the inner contour of the cam.

The cam 57 at each end of the machine is engaged by a follower 59 on one arm of a bell-crank lever 60, the other arm 61 of which has a tension spring 62 attached thereto, the opposite end of the spring being secured to the frame rod 24 so as to hold the follower 59 against the surface of the cam. The bell-cranks 60, 61 are pinned to a hollow rock shaft 63 which carries at regular intervals along its length fingers 64 having on their free ends stops 65 which are adapted to protrude through slots in the plate 40 and into the notches formed at the upper edge of the plate 39. Stop means differing in detail from that shown could, of course, be employed. As will be apparent from an inspection of Fig. 1, the rotation of the cam 57 will cause the stops 65 to project into the path of movement of the sheets between guide plates 39 and 40 at timed intervals, and to be withdrawn therefrom.

Each of the frame members 23 has a relatively slender upward extension 66. These extensions carry pivot pins 67 from which are pivotally suspended a pair of swinging guide plates 68 and 69 that are secured together at their ends so as to remain in rigid relation with each other and move as a unit. When the plates 68 and 69 are in their normal position, illustrated in Fig. 1, they provide a path for the movement of sheets which is in effect a continuation of the path provided by the plates 39 and 40. The plate 69 is continued at its lower end in a wide curve 70, in order to present at all times a smooth and non-angular surface to the sheets being fed.

The swinging guide 68, 69 is pulled toward its normal position by a coil spring 71, one end of the latter being attached to a pin 72 mounted in the outer end of bracket 46. On the plate 68 near the ends thereof are pairs of perforated lugs 73. Between each such pair of lugs I mount an eye-bolt 74. On each of these eye-bolts is mounted a U-shaped clamp 75 provided with downwardly extending portions for the support of a rod 76. Upon the latter, at each end of the feeder, is pivoted one end of a lever 77, the opposite end being pivotally mounted upon the frame rod 26. Each lever 77 carries intermediate its ends a cam follower 78 that runs upon the adjacent

cam 58. One half of this cam is circular and the other half has one high spot with a symmetrical approach and descent from and to the circular portion. It will be apparent, therefore, that through one-half the cycle of movements the guide 68, 69 is in its full line or normal position, while during the remaining half of the cycle it is swinging from this normal position to the dotted line position and back again.

Outside the bearing 51 a bushing 79 surrounds the shaft 50 and serves as a bearing for a sleeve 80. On one end of the latter there is fixed a gear 81, which meshes with any driving gear on the Rotaprint or other machine to which the feeder of the present invention may be attached. Preferably the gear 81 meshes for this purpose with a gear 150, Fig. 6, which in turn has driving connection with roll 102. On its opposite end the sleeve 80 is provided with a circular flange 82 having a hole 83 therein. The outer end of the shaft 50 beyond the sleeve 80 has pinned thereto a disc 84 provided with a circular flange 85, enclosing the flange 82 of the sleeve and preferably knurled on its outer surface. In this disc there is a slot 86 of arcuate shape. A kidney-shaped plate 87 covers a portion of this slot and has formed integral therewith a sleeve 88 which extends perpendicularly to the plate and whose diameter is only slightly less than the width of the slot. Within this sleeve is a plunger or pin 89 having a knurled wheel 90 pinned to its outer end, the hub of the wheel being provided with an extension 91 which takes into a slot in the sleeve member 88. A coil spring 92 surrounds the small diameter portion of pin 89 and tends to hold the pin in the hole 83. When the operator desires to declutch the two plates 82 and 84, he grasps the wheel 90, pulls it out far enough to enable the extension 91 to clear the slot in the sleeve 88, which is also far enough to withdraw the pin 89 from the hole 83. He then turns the wheel 90 through part of a revolution so that the extension 91 rests upon the outer end of the sleeve 88, thereby holding the pin 89 in its withdrawn position. The plates 82, 84 are then, of course, free to rotate relatively to each other. The plate 87 on either side of the sleeve 88 has a bolt hole therein through which extend bolts 93, the heads of the latter being flattened on one side, as indicated in Fig. 12, to prevent rotation. Washers 94 and nuts 95 on the inner ends of these bolts serve to secure the plate 87 in place. However, when the nuts 95 are loosened, the plate 87 may be moved angularly through a considerable arc for the purpose of adjusting the angular position of the pin 89 in the plate 84. By this means, the relation of the paper feed to the printing surface of the printing machine is easily and quickly varied or adjusted.

On the protruding end of the shaft 50 secure a crank 96 to which is attached a connecting rod 97, the opposite end of which is pivotally joined to the upper end of the oscillating suction head 13 for driving the latter. By this means the operations of the suction head are timed with the operations of my feeder, one sheet being delivered to the feeder for each revolution of the shaft 50.

For the purpose of illustrating one of the applications of the invention, I have shown herein, somewhat diagrammatically, the principal parts of a Rotaprint machine, the plate roll being illustrated at 100, the blanket roll at 101, and the back roll at 102. Their directions of rotation are indicated by arrows. It will be understood that the plate roll and the blanket roll each make one revolution for every revolution of the shaft 50 of my feeder. In machines of this character, I have found that there is a strong tendency for the paper sheets to adhere to the surface of the blanket roll. Hence a stripper must be provided in order to insure the proper feeding of the paper. For this purpose, I have evolved a novel construction which will now be described.

Within the recess 103 of the blanket roll between the ends of the blanket, I fix a rod 104 which runs parallel to the axis of the roll from end to end thereof. This rod is supported at its ends in brackets 105 which are secured to the roll by studs which extend through slots 106 in the brackets. A stripper bar 107 fits over the rod 104, being provided with a slot 108 which loosely receives the rod, this slot being deeper at its ends than in the middle, as will be apparent from an inspection of Fig. 9. The ends of the bar have attached thereto retaining straps 109 that extend around the rod 104 but permit a slight movement of the bar toward and away from the rod. Thus the bar 107 in a sense "floats" upon the rod 104.

The outer surface of the bar 107 is concave, its curvature corresponding substantially to that of the back roll 102 with which it cooperates. This outer surface has formed there-in a series of transverse slots 110, the bottoms of which are formed on a convex curve. Torsion springs 111 anchored in the brackets 105 and in the straps 109, as shown in Fig. 9, tend to hold the rear edge of the stripper bar outwardly, as indicated in the dotted line positions of the bar in Figs. 1 and 10.

112 are a series of guide wires which are mounted on parallel rods 113 and 114, these wires being positioned so as to come directly opposite the grooves 110. Below the horizontal portions of the wires 112 I may mount a flat plate 115 to guide the sheets into any suitable delivery means, not shown. In order to assist in the stripping of the paper after the stripper bar has moved out of contact with the paper, I provide wheels 116, posi-

tioned near the sides of the machine where they are adapted to run upon the margins of the paper. These wheels are caused to bear resiliently upon the surface of back roll 102, being mounted upon levers 117 pivoted at 118, the upper ends of which are under pressure from coil springs 119. The supports for the wheels 116 are adjustable transversely upon the rods 113 and 114. As the forward 10 edge of a sheet of paper leaves the guide 68, 69, it passes between the roll 102 and the rear edge of the stripper bar 107. That bar is then gradually rocked upon its pivot 104 by contact with the roll 102 against the tension 15 of springs 111 until it takes the full line position of Figs. 1 and 10, when the forward edge of the sheet is firmly gripped between the roll 102 and the bar 107. Further rotation of the roll 101 permits the spring 111 to swing the 20 bar 107 upon its pivot, thereby holding the rear edge of the bar against the back roll 102 with sufficient pressure to continue the feed of the sheet, so that the forward edge of the latter is well under the wires 112 before the stripper bar lets go.

On the frame rod 26 between the levers 77, I mount a wooden roller 120, a bushing 121 being preferably interposed between the roller and the rod. This roller is for the 30 purpose of guiding paper in web form upwardly from a rotatably mounted roll of paper (not shown) to one side of the sheet feeder and thence into the printing machine. All that is necessary in order to make 35 this change is to declutch the plates 82 and 84, as previously explained, and to start the web feed. Paper in sheets or in web form is therefore equally available for use upon the machine.

40 *Operation.*—With regard to the operation of the sheet feeder, assuming that a pile feeder is hooked up to the machine, as indicated in Fig. 6, and assuming that the clutch pin 89 is in operative position, the motor of the 45 printing machine is started, causing the rotation of crank 96, which imparts oscillating movement to the suction head 13 through connecting rod 97. At each revolution of the crank 96, therefore, a sheet is removed from 50 the pile 12 and is placed upon the conveyor 18 which moves the sheet forward through the feed rolls 37, 38 into the fixed guide 39, 40 and up against the stops 65, the sector 53 and the other parts attached to shaft 50 55 then being in a position somewhat less advanced than that shown in Fig. 1, so that the sector 53 does not protrude into the path of movement of the sheet nor hamper its travel. 60 Immediately after the shaft 50 reaches the position illustrated in Fig. 1, the follower 59 runs up onto the outer contour of cam 57, retracting the stop fingers 65, and the follower 48 descends to the inner contour of cam 56, thereby permitting springs 47 to move 65 feed rollers 41 inwardly where they run upon

the paper sheet and hold it against the positively moving sectors 53. The sheet is thereby fed forward in a positive manner and enters the space between guide plates 68 and 69. It travels through the guide 68, 69, and 70 its forward edge is gripped between the stripper bar 107 and back roll 102, as previously explained, the bar 107 having progressed by that time from the position of Fig. 1 to that of Fig. 10. Thereafter a positive feeding 75 movement is imparted to the forward edge of the sheet by the printing rolls and by wheels 116.

Shortly after this occurs, the high part of the cam 56 again engages the follower 48 80 and the rollers 41 are thereby forced out of contact with the paper sheet so that the rear edge thereof is then free and the sheet is fed only by the action of the rolls 101 and 102 and the wheels 116. At about the time the 85 rear end of the sheet is thus released, the high spot of the cam 58 begins to lift the follower 78 and to swing lever 77 upwardly around the rod 26 as a pivot, and the resultant movement of the pin 76 in an arc of a circle swings the 90 guide 68, 69 upon its pivot 67 from the full line position to the dotted line position. The plate 69 is thereby caused to pull transversely upon the sheet, swinging the free rear portion thereof out of the direct path of movement 95 of the sheet and pulling it entirely clear of the fixed guide 39, 40. In the course of this swinging movement, the sheet contacts with the curved portion 70 of the plate 69 further and further toward the outer edge thereof, 100 but at all times the sheet is moved over a curve of large radius so that its travel is not interfered with. At about the time the guide plates 68, 69 are at the furthest point of 105 their swing, the follower 59 descends onto the inner contour of the cam 57, causing the stop fingers 65 to again move across the path of the sheets in the guide 39, 40 ready for engagement with the next sheet advancing along the guide. In the meantime, the swinging guide 68, 69 is returning to its full line 110 position. The cycle of operations as above described then repeats itself.

The depth of the margin above the printing upon the upper edge of the sheet will depend upon the distance to which the sheet is advanced when the printing surface begins to contact with the paper. This may be varied considerably with my mechanism on account of the fact that the stripper bar 107 is adapted to grip the sheet when its forward 115 edge is at any one of various points between the forward and rear edges of the bar. In other words, the sheet does not need to meet gripping fingers set at a definite point in the 120 periphery of the printing roll, as is usual. Hence I am enabled to obtain margins of various depths at the top of the sheet by merely changing the angular position of the pin 89 in the disc 84, as previously described, thereby 125 130

advancing or retarding the feed of the sheets with respect to the rotation of the roll 101.

It will be obvious that the concave surface of the stripper bar 107 holds the sheets against the back roll 102 until their forward edges have traveled to a greater or lesser extent under the guide wires 112. It will also be apparent that the rear edge of stripper bar 107 is held against the roll 102 by the torsion springs 111 until the paper is well entered beneath the wires 112, even though the feed adjustment be such that the forward edges of the sheets lie but a short distance beyond the rear edge of the stripper bar.

15 The rod 104 is resilient, and, in practice, the brackets 105 are so set that when the stripper bar engages the roll 102 the rod 104 is flexed. In this manner the bar 107 is held against the roll 102 under spring pressure. 20 On account of the fact that the slot 108 tapers toward the middle, the bar 107 may adjust itself to the roll 102 accurately by a lengthwise tilting action.

While in the foregoing description and in 25 the accompanying drawings, I have disclosed more or less in detail one particular embodiment of the invention, I desire it to be understood that such detailed disclosure is primarily for the purpose of fully illustrating 30 the invention and is not to be construed as amounting to a limitation upon its scope.

Having thus described my invention, I claim:

1. A method of feeding sheets in close succession, which consists in causing each sheet to impinge against a stop, withdrawing the stop and continuing the feed, and moving the rear edge of the sheet independently of the feed thereof out of the way of said stop.

40 2. A method of feeding sheets in close succession along a given course and straightening them in that course, which consists of interposing a stop against which the forward edge of each sheet impinges and by which 45 its travel is temporarily interrupted, withdrawing the stop from the path of movement of the sheet, imparting a positive feeding movement to the sheet in advance of said stop, and moving the sheet transversely 50 of said path between the stop and said positive feeding means, whereby the rear end of the sheet is drawn laterally away from said stop.

3. A method of feeding and aligning 55 sheets travelling in close succession, which consists in advancing the sheets through a given path one at a time into contact with a front end stop to straighten the sheets, with drawing said stop, continuing the feed of each sheet into a pivoted guide and through the same until the forward end of the sheet is gripped by moving elements producing further feeding of the sheet, swinging the rear end of the pivoted guide to draw the rear end 65 of the sheet out of said path, and thereafter

moving said stop into operative position for engagement with the next sheet.

4. In a sheet feeder, a stop means, means for feeding a sheet against said stop means, means for withdrawing the stop means and 70 continuing the feed of the sheet, a movable guide adapted to receive the sheet and guide the same in its further forward travel, and timed means for moving said guide transversely of the path of the sheet, whereby the rear end of the sheet is drawn out of the path 75 of movement taken by the forward end thereof.

5. In apparatus of the class described, 80 guiding means for directing the travel of sheets in close succession along a given path, a stop moving into said path for engagement with each sheet to straighten the same and then moving out of said path, a positive sheet feeder in said path in advance of said 85 stop, a portion of said guiding means between said positive feeder and said stop being movable transversely, and means for moving said portion to produce lateral movement of the rear end of each sheet during 90 the period when said stop is withdrawn.

6. In apparatus of the class described, 95 guiding means for directing the travel of sheets in close succession along a given path, a stop moving into said path for engagement with each sheet to straighten the same and then moving out of said path, a positive sheet feeder in said path in advance of said stop, a portion of said guiding means between 100 said positive feeder and said stop being pivotally mounted near its forward end to swing transversely of the said path of movement, and means for swinging said portion upon its pivot to produce lateral movement 105 of the rear end of each sheet during the period when said stop is withdrawn.

7. In a sheet feeder, two sets of positive feeding means spaced apart along a path of sheet travel, means for disabling the rear feeding means after each sheet is gripped 110 by the forward feeding means, and means interposed between said two feeding means movable transversely of said path of travel for moving the rear end of each sheet laterally after it is released by the rear feeding means.

8. In a device of the class described, a laterally swinging sheet guide comprising a pair 115 of spaced plates between which the sheet is fed, and means timed with the feed of the sheets for swinging said guide to bring the rear end thereof to a position to one side of the direct path of movement of the sheets, one of said plates having a curved rear end 120 adapted to engage said sheets in the displaced position of said guide.

9. In combination, a sheet feed mechanism, 125 driving means therefor adapted to be geared to a printing machine to operate in timed re-

lation therewith, said means comprising two adjacent rotary members turning about the same axis, a longitudinally slideable pin eccentrically mounted in one member adapted to fit into a hole in the other member, and means for angularly adjusting the mounting of the pin in its member.

meet said gripping device at different positions angularly of its roll.

In testimony whereof, I hereunto affix my signature.

THOMAS WALTER HORN. 70

10. In mechanism of the class described, a pair of cooperating rolls, a paper stripper carried by one of said rolls, means for feeding a sheet between said rolls at each revolution of said stripper, said stripper in the one roll covering a substantial sector of the other roll as the stripper passes between the rolls, and means for varying the timing of the sheet feed with respect to the stripper rotation, whereby the forward edge of each sheet may be caused to assume positions at various distances in advance of the rear edge of the stripper.

11. In a machine of the class described, a roll having a longitudinal recess therein, a stripper bar in said recess mounted upon a longitudinal pivot located in the recess, said stripper bar having a concave outer surface, and means resiliently holding outward the rear edge of said stripper bar.

12. In combination, a frame adapted to support printing mechanism, a sheet feeder adapted to be removably mounted in the frame, and a deflecting roller carried by said sheet feeder over which a paper web is adapted to run, whereby the feeder may be permitted to remain in operative position during the use of the machine for printing from a paper web.

13. In combination, a frame adapted to support printing mechanism, a sheet feeder adapted to be removably mounted in the frame, driving means for said sheet feeder adapted to be operatively connected with the printing mechanism, said driving means being readily disconnectable, and a deflecting roller carried by said sheet feeder over which a paper web is adapted to run, whereby the operation of said sheet feeder may be interrupted and paper in a web may be fed to said printing mechanism without removing said sheet feeder from the frame.

14. In combination, a pair of cooperating rolls, a sheet gripping device mounted upon one of said rolls adapted to cooperate with the other roll to grip the forward edge of a sheet at any position within a substantial angle of the circle of rotation, a sheet feed mechanism, driving means therefor adapted to be geared to said rolls, whereby the feeding of sheets may be timed with respect to the rotation of said rolls, said means comprising two concentric rotary members, and means for locking said members together in any one of a plurality of angular relations, whereby the feed of sheets may be varied to cause the forward edges of the sheets to
